UNITED STATES PATENT OFFICE.

STRICKLAND L. KNEASS, OF PHILADELPHIA, PENNSYLVANIA, ASSIGNOR TO WILLIAM SELLERS & COMPANY, INCORPORATED, OF PHILADELPHIA, PENNSYLVANIA, A CORPORATION OF PENNSYLVANIA.

INJECTOR.

Application filed August 5, 1926. Serial No. 127,306.

My invention relates to improvements in injectors and more particularly to the provision of a retarding valve in association with a supplemental steam control valve in connection with an exhaust injector.

Heretofore there have been provided injectors of a type utilizing in their operation, both exhaust and live steam and such injectors have proved of substantial value and especially so when used on locomotives, in connection with which they are of value because of an economical use of steam and because of the fact that they are so designed as to utilize heat from exhaust steam to pre-
heat the feed water, thus returning some of the heat of the exhaust to the boiler. The details of construction of an injector of the type referred to are fully disclosed in the United States patent granted to me May 26, 1925, No. 1,539,319.

In connection with the use on a locomotive of an injector of the type utilizing both exhaust and live steam, there has been heretofore provided control means for admitting a supply of live steam at low pressure to the injector, when the supply of exhaust steam is not available, due to the drifting or stopping of the locomotive, and such control means are designed to operate automatically, usually under the influence of the pressure of steam supplied for operation of the locomotive. The details of construction of control means for injectors of the type indicated are fully disclosed in United States Letters Patent issued to me November 24, 1925, No. 1,563,196.

In practice injectors of the type indicated, in association with controlling means for enabling a supply of live steam at reduced pressure when necessary, have proved efficient and economical for use on locomotives. However, the result may not be wholly satisfactory owing to the frequent changes in the operating conditions of the locomotive when near the limit of its tractive power.

Even under more normal conditions of railroad service, changes affecting the operation of the injector occur when the locomotive is shut down to permit it to drift or to be brought to a stop; under such conditions,

no exhaust steam is available and the necessity for a supply of live steam arises. Again, if the locomotive be drifting or at a standstill, with the injector in operation, and the throttle be opened, exhaust steam again becomes available and the desirability arises for its substitution for live steam as a source of supply for the injector.

Under the varied conditions of locomotive operation, if it be that the injector is required to be continuously operated, certain difficulties are met with due to the time element in the change of operating conditions. For example, if the locomotive be standing, or drifting, both the high and low pressure steam supplies necessary for operation of the injector are drawn directly from the boiler. When the throttle is opened to start the engine, steam from the steam chest at once acts to operate the means for controlling the supply of low pressure steam to the injector. As a result, the supply from the boiler may be shut off before sufficient exhaust steam be available to supply the requirements of the injector. Thus, the operation of the injector is interfered with, by the temporary cut off of the supply of low pressure steam, and hand manipulation is required for re-starting.

Under the varied conditions of locomotive operation, it has also been found that the means for controlling the source of low pressure steam supply cannot be relied upon to operate with certainty of simultaneous action or at predetermined pressures and it has been appreciated that due to the range of pressures which exist in the steam chest of a locomotive, during idling, part load and full load, there may be certain pressures under which the control means may not correctly function owing to a balancing of pressures, or too prompt or delayed action of the control valve mechanism relative to the main steam supply.

Now it is an object of my invention to provide means, more particularly a retarding valve, for controlling the operation of the means for controlling the source of supply of low pressure steam to the injector in such a manner as to insure a supply of exhaust

steam before the supply of low pressure steam from the boiler is shut off. Further, to control the low pressure steam supply means, and particularly the means for controlling the supply from the boiler, so as to insure its positive action with predetermined pressures in order to effectively meet the conditions of locomotive service. A still further object of my invention is to control the flow of actuating steam from the steam chest to the control means so that the opening of the live steam admission valve may be instantaneous, and the closing shall be retarded until the required flow of exhaust steam from the cylinders to the injector is obtained.

Having now indicated, in a general way, the nature and purpose of my invention, I will proceed to a detailed description thereof with reference to the accompanying drawings in which there is illustrated a preferred embodiment and in which:

Fig. 1, is a view showing a portion of a locomotive cylinder and steam chest, with means for controlling the source of low pressure steam supply to the injector in association with means embodying my invention.

Fig. 2, is a sectional view of a retarding valve embodying my invention.

Fig. 3, is a cross section on line 3—3 Figure 2.

Referring more particularly to Figure 1, *a* indicates a locomotive cylinder, associated with which is a steam chest *b*. The cylinder is supplied with steam, under the control of the usual valves, from the steam chest to which steam is admitted under the control of a throttle valve. *c* indicates a conduit connected to the low pressure side of an injector, not shown, but which may be of the character shown and described in Letters Patent No. 1,539,319, granted to me May 26, 1925, and *d* indicates a conduit into which exhaust steam from the cylinder flows. The conduits *c* and *d* are connected by a valve body *e* containing supply valves controlled by the pressure of steam in the steam chest, being in connection therewith through a pipe *f*. The supply valves within body *e* control the admission to conduit *c* of live steam from a pipe *g*, connected with the boiler, or of exhaust steam from conduit *d*.

The structure of the valves in body *e* and of the means for controlling them under the influence of pressure in the steam chest is fully disclosed in U. S. Letters Patent No. 1,563,196, granted to me November 24, 1925.

In accordance with my present invention I provide a retarding valve, with a body *h* positioned between the steam chest and the means for operating the supply valves in body *e*, which operating under the influence of pressure in the steam chest will control the effective influence of the steam chest pressure on the operation of the supply

valves and insure their timely and positive operation.

The valve may be positioned on the steam chest as shown in Figure 1, or it may be positioned at any convenient or desired point in pipe *f*, or in the supply pipe to the steam chest. The details of the construction of the valve *h* and its mode of operation will be understood by reference to Figure 2.

Referring now to Figure 2, *h* represents a valve body provided with a flange *i* for attaching to the steam chest *b*, or in the steam supply line from the boiler to the steam chest. The body is provided with a steam inlet *j*, in communication with the steam chest, and an outlet *k*, connected to pipe *f*. The body is also provided with an outlet *l* to atmosphere. A partition or wall *m*, having a central aperture *n*, separates the inlet *j* from the outlet *k* and forms a chamber *z*, within the casing, in communication with atmosphere through outlet *l*.

A valve *o*, having an upper guide *p* and a lower guide formed by wings *p'*, and lower and upper valve faces *q* and *r*, is positioned within the casing with the wings *p'* within the aperture *n* in wall *m*, so that the lower valve face *q* may seat on a seat *s* on wall *m*, at the lower end of the stroke of the valve, the upper valve face *r* being adapted to seat on a seat *t* screwed into the casing, at the upper end of the stroke of the valve. The upper guide *p* is entered in a recess in a cap *u* threaded into the top of the casing. A spring *v* on the upper guide *p* is confined between the cap *u* and the valve, its tension being set to exert a predetermined pressure on the valve.

The wall *m* from its upper surface is provided with a cylindrical bore, concentric with the aperture *n*, in which fits an enlargement *w* formed on the valve, above its lower face *q*. In the periphery of the enlargement *w* is formed a discharge slot *x*, of required area to obtain delayed action of the means for controlling the admission valves when closing the live steam admission valve and opening exhaust steam regulating valve.

Steam from the steam chest may pass between the webs *p'* to the under side of the valve *o*. It first exerts a pressure on the valve, when the valve is down, and then on enlargement *w* when the valve is first raised, compressing the spring *v* and closing the outlet *k* to atmosphere by seating the face *r* on seat *t*.

It will now be noted that the spring *v* acts to retain the valve *o* in lower position with its lower face *q* on seat *s* when there is less than a predetermined pressure, or no pressure in the steam chest, as when the throttle is partly or wholly closed. In the lower position of the valve the chamber *z*, pipe *f* and slot *x* are in communication with atmosphere through outlet *l*.

If pressure builds up in the steam chest to the predetermined pressure, due to the opening of the throttle, steam will pass through inlet *j*, and between webs *p'* and exert a pressure on the valve *o*, which will be resisted by the pressure of spring *v* until such time as the steam chest pressure reaches a predetermined degree capable of overcoming the pressure of spring *v*. When the steam pressure acting on the valve *o* is sufficient to overcome the action of spring *v*, the valve will be lifted and the enlargement *w* will be subjected to the full pressure of the steam. The steam pressure acting on the valve *o* and on the enlargement *w* will instantly overcome the increased force of the spring and lift the valve to its upper position against the upper seat *r*, closing the outlet *l* and permitting flow of steam through the restricting passage *x*, which causes a gradual accumulation of pressure in chamber *z* and pipe *f*. When the pressure in pipe *f* reaches the degree necessary for actuating the means for controlling the admission valves, they will be actuated to shut off the live steam supply and open the exhaust. It will be noted that due to the restricted opening *x* there will be a substantial delay in the operation of the control means after the steam chest pressure reaches the degree necessary to actuate valve *o*.

It will be noted that when the valve *o* initially lifts, under the pressure beneath it, any steam passing into chamber *z* through the slot *x* may escape through outlet *l*, so that such steam will have no effect on the injector supply control valves, but that, after the initial lift of the valve, when the predetermined pressure acting on the enlargement *w* lifts the valve to its upper position the outlet *l* will be instantly shut off and the steam admitted to chamber *z* and pipe *f*, when the required pressure is built up therein, will pass to and function to actuate the supply valves. The steam enters chamber *z* only through slot *x*, however, and it will be observed that since the size of the slot *x* is limited, a predetermined time will elapse after the valve *q* is lifted before the supply valves will be actuated to shift the injector supply from boiler to exhaust. Thus it will be observed that irrespective of the fact that steam is admitted to the steam chest by opening the throttle, steam will be prevented, or delayed, by valve *o*, from passing into pipe *f* and acting to operate the injector supply control valves, to change the supply from boiler to exhaust, until a predetermined pressure is built up in the steam chest and until a requisite pressure is built up in pipe *f* after the opening of the valve *o*.

When the supply of exhaust steam becomes insufficient for the requirements of the injector, for example, due to closing of the throttle, the pressure in the steam chest and

hence in the inlet *j* will drop and the valve will be instantaneously forced down into lower position, by the spring *v*, and the chamber *z* will be opened to the atmosphere and the pressure therein relieved through outlet *l*, allowing the supply control valves to be instantaneously reversed to provide a supply of live steam to the injector from the boiler.

By virtue of my invention the shifting of the supply valves from boiler supply to exhaust supply immediately on opening the throttle and before the cylinder has a chance to exhaust, is avoided and the injector is insured of a supply from the boiler until a sufficient supply from the exhaust is available.

Further, the supply valves operating means is not subjected to such steam chest pressure, within wide limits, as may be available at any given time, but it is assured that it will not be subjected to less than a predetermined pressure, which will be not less than necessary to effect operation of the valves simultaneously and positively.

Having now fully described my invention, what I claim and desire to protect by Letters Patent is:—

1. Means for continuously supplying steam at low pressure to an injector on a locomotive having a working cylinder comprising in combination means for controlling an exhaust steam supply, means for controlling a live steam supply, means associated with said means adapted under the influence of live steam pressure to automatically actuate said means to admit exhaust steam to said injector when exhaust is available and to admit live steam when exhaust is not available and means for delaying the admission of exhaust steam after exhaust becomes available and for permitting instantaneous admission of live steam when exhaust is not available.

2. Means for continuously supplying steam at low pressure to an injector on a locomotive having a working cylinder, comprising, in combination, an exhaust steam supply valve, a live steam supply valve, means associated with said valves adapted, under the influence of live steam pressure, to automatically reverse them to permit a supply of exhaust steam to the injector when the locomotive is working and a supply of live steam at reduced pressure when the locomotive is not working and means for retarding the access of live steam to said last mentioned means when the locomotive is put to work until a supply of exhaust steam is available.

3. Means for continuously supplying steam at low pressure to an injector on a locomotive having a working cylinder, comprising, in combination, an exhaust steam supply valve, a live steam supply valve,

means associated with the said valves adapted, under the influence of live steam pressure, to automatically reverse them to permit a supply of exhaust steam to the injector when the locomotive is working and a supply of live steam at reduced pressure when the locomotive is not working, a restricted passage for steam to said last mentioned means and a valve adapted to prevent the entry of steam to said passage at less than a predetermined pressure.

4. Means for continuously supplying steam at low pressure to an injector on a locomotive having a working cylinder, comprising, in combination, an exhaust steam supply valve, a live steam supply valve, means associated with said valves adapted, under the influence of live steam pressure, to automatically operate them to permit a supply of exhaust steam to the injector when the locomotive is working and a supply of live steam at reduced pressure when the locomotive is not working and a valve adapted under the influence of spring pressure to delay the access of live steam to said last mentioned means. •

5. Means for continuously supplying steam at low pressure to an injector on a locomotive having a working cylinder, a steam chest associated therewith and a throttle controlling the admission of steam to the steam chest, valves controlling the admission of exhaust and live steam at low pressure to said injector, means adapted to actuate said valves under the influence of steam pressure, a conduit affording a passage for steam from the steam chest to said means for actuating said valves, a restricted inlet to said conduit, a valve controlling said inlet and a pressure means adapted to act on said valve to position it against pressure in the steam chest to prevent the passage of steam into said conduit and adapted to yield to permit the valve to open under a predetermined pressure in the steam chest.

6. Means for continuously supplying steam at low pressure to an injector on a locomotive having a working cylinder, a steam chest associated therewith and a throttle controlling the admission of steam to the steam chest, valves controlling the admission of exhaust and live steam at low pressure to said injector, means adapted to actuate said valves under the influence of steam pressure, a conduit affording a passage for steam from the steam chest to said means for actuating said valves, a valve in said conduit, and a spring adapted to act on said valve to position it against pressure in the steam chest to prevent the passage of steam into said conduit, and adapted to yield to permit the valve to open under a predetermined pressure in the steam chest.

7. Means for continuously supplying steam at low pressure to an injector on a locomotive

having a working cylinder, a steam chest associated therewith and a throttle controlling the admission of steam to the steam chest, valves controlling the admission of exhaust and live steam at low pressure to said injector, means adapted to actuate said valves under the influence of steam pressure, a conduit affording a passage for steam from the steam chest to said means for actuating said valves and having an opening to atmosphere, a double faced valve in said conduit, a pressure means adapted to act on said valve to position it against pressure in the steam chest to prevent the passage of steam into said conduit and to open said opening to atmosphere and adapted to yield to permit the valve to be positioned under a predetermined pressure in the steam chest to permit the passage of steam into said conduit and to close said opening to atmosphere whereby actuation of said exhaust steam admission valve will be delayed and actuation of said live steam admission valve will be instantaneous.

8. Means for controlling a supply of steam at low pressure to an injector operated wholly or partly with exhaust steam from an engine including means controlling the admission of exhaust steam to an injector, means controlling the admission of live steam to the exhaust steam supply, means adapted to act to cause said aforementioned means to interact and means acting to delay the action of said last mentioned means in effecting admission of exhaust steam to the injector.

9. Means for controlling the supply of steam at low pressure to an injector operated wholly or partly with exhaust steam from an engine, including means controlling the admission of exhaust steam to the injector, means controlling the admission of live steam to the exhaust steam supply, means adapted to act to cause said aforementioned means to interact when live steam is admitted to or shut off from the engine cylinder and means adapted to delay the action of said last mentioned means when live steam is admitted to the engine cylinder.

10. Means for supplying steam at low pressure to an injector operated wholly or partly with exhaust steam including a valve controlling the admission of exhaust steam to the injector, a valve controlling the admission of live steam to the injector, means adapted to cause said valves to interact automatically and means adapted to delay opening of said valve controlling the admission of exhaust steam and to permit substantially instantaneous opening of said valve controlling the admission of live steam.

11. Means for supplying steam at low pressure to an injector operated wholly or partly with exhaust steam including a valve

controlling the admission of exhaust steam to the injector, a valve controlling the admission of live steam to the injector, means adapted under the influence of live steam pressure to cause said valves to interact, a conduit affording a passage for live steam to said last mentioned means and means for

restricting the entry of live steam into said conduit.

In testimony of which invention, I have ¹⁰ hereunto set my hand, at Philadelphia, Penna., on this 29th day of July, 1926.

STRICKLAND L. KNEASS.
